SEPARATION OF SALTS OF ORGANIC ACIDS

Vaman R. Kokatnur, New York, N. Y.; Helen G. Kokatnur, executrix of said Vaman R. Kokatnur, deceased

No Drawing. Application September 20, 1948,
Serial No. 50,241

3 Claims. (CL. 260—97.6)

1

This invention is a continuation in part of my co-pending application Serial No. 569,643, filed December 23, 1944, now abandoned, and relates to the separation of fatty acid and hydro-aromatic acid such as resin or rosin acid soaps in a commercially useable form from the crude wet floating soap, a by-product of kraft paper pulp industry.

Floating soap of the sulfate pulp industry may be termed as crude kraft soap or crude tall oil soap. It is a by-product in the treatment of slash or southern pine, spruce, etc., by the sulfate process to produce wood-pulp. The composition of this soap comprises essentially sodium salts, of resin or rosin acids, i. e., mainly abietic acid, and of fatty acids, such as oleic, linoleic, linolenic, ricinoleic acids. In exceptional cases, very small amounts of saturated fatty acid salts may be present. The black liquor when separated after cooking the wood from pulp, chips, etc. and allowed to stand, yields what is known as floating soap as a scum on the top. This is due to salting out of the soap by the excess sodium ions in the black liquor a phenomenon analogous to the salting out step in soap manufacture.

The floating soap is of value not only because of the high content of higher fatty acid salts but because of sodium abietate or resinate which is a valuable sizing material for paper. The fatty acid soap when separated as relatively pure soap is a valuable detergent and if separated in the form of free acids and then esterified produces a good drying oil useful in the paint and varnish industry. The resin or rosin acids also have drying characteristics, although not useable in this form, but produce when esterified a valuable resin known in the trade as ester gum. The soap or acid in the crude form is a relatively valueless mixture that has found no utility in commerce.

Many prior attempts have been made to separate the acid constituents of tall oil which is nothing more than a mixture of all the total acids in the crude floating soap. Although the art is very extensive, there is but little information regarding the separation of crude soap itself into commercially useable relatively pure soaps of fatty acids and resin or rosin acids. The prior art is replete with methods of separating the acids by high vacuum distillation, differential separation by esterification of one type of the constituents or separation by selective solvent action on the mixed acids. So far as I know no one has successfully solved the problem of separating the two types of soaps, viz, fatty acid soaps

2

and resin acid soaps, from the crude kraft floating soap, or a rosin soap from a fatty acid.

I have discovered that the two main types of soaps, viz, fatty acid soaps and resin acid soaps, can be easily, efficiently and economically separated, and of a quality directly useable as detergents and sizing compositions.

It has been considered heretofore that the two types of soaps in the crude floating soap have the same or equal solubilities in solvents and cannot be separated from each other by selective solvent action without tedious plurality of operations that are uneconomical.

I have now discovered that certain ketones in the presence of a critical proportion of dissolved water, bring about the separation of fatty acid soaps by selective solvent action on the resin or rosin acid soaps. The dissolved soaps of resin can be separated from the undissolved fatty acid soaps by mere filtration and washing at room temperature. The resin or rosin acid soaps can be isolated by merely removing the solvent by evaporating or distillation.

The resin acid soap is more sensitive to oxidation than the fatty acid soap although both contain constituents that are subject to oxidation even at atmospheric temperatures when exposed to air. The oxidation, of course, is enhanced at higher temperatures and is directly proportional to its increase. The crude wet soap as originally obtained contains no oxidized ingredients inasmuch as the soap is normally associated during wood cooking with Na_2S , a reducing agent. Further, no manufacturer has reported the presence of any oxidized substances in such soap.

Linoleic, linolenic and resin acids are drying acids, that is, they absorb oxygen and polymerize forming high molecular weight, relatively insoluble solid compounds. When a drying oil such as linseed, tung or dehydrated castor oil dries by absorption of oxygen in the presence of driers a solid, relatively insoluble film is produced. When completely oxidized, it increases in weight by about ten percent for every double-bond of the unsaturated acid provided that there are about two double-bonds to each acid molecule.

Drying oils on the average contain not more than two double-bonds to each monobasic molecule or about six to a natural oil molecule, which is a glyceride and hence tri-basic. The well-known linseed oil contains on the average two double-bonds per monobasic molecule. No natural oil is known that has a materially higher

iodine number, a measure of the double bonds, than this linseed oil. This means then that when a natural oil oxidizes or dries completely, it increases in weight by about twenty percent. Dried or oxidized oil is not an oil, physically or chemically, although it may contain some unoxidized oil. The solubility of an oxidized oil is radically different in any given solvent than the oil un-oxidized.

Experiments show that floating or tall oil soap when dried by exposure to air increases in weight by six to twelve percent and if spray dried, between twelve to eighteen percent, and is converted to a composition which is radically different from that of the original in solubility, odour, color, melting point and other physical and chemical properties. It is an interesting fact that this weight increase is particularly noticeable in the resin or rosin soap and negligible in the fatty acid soap. If, however, the soap contains any traces of cobalt or manganese salts, both soaps increase in weight. The increase of weight during drying in contact with air apparently depends upon the contact surface of the soap during drying, temperature, composition of the crude soap particularly with respect to resin or rosin acid content and lastly the presence or absence of metal impurities that may be considered as dryers or siccatives. For these reasons, I dry the crude wet soap preferably either in contact with some volatile solvent or in the presence of an inert gas such as nitrogen or carbon dioxide or in the absence of air, i. e., vacuum.

The suitable solvents that may be used for drying or dewatering the crude soap, are ketones containing not more than six carbon atoms, ethers such as isopropyl ether, methyl Cellosolve, dioxane, etc., but not alcohols, particularly monohydric alcohols, as both the soaps are considerably soluble in them. In my invention, drying the soap is not an essential part or step of the process. Inasmuch as by mixing the wet soap with a relatively dry solvent in such an amount that by taking up and dissolving the water of the soap it becomes a selective solvent of the resin or rosin soap, a separate step of drying is not essential, and efficient separation can be effected by the mixing and filtering the mixture. The soap on the filter is a relatively pure unoxidized fatty acid soap and the soap dissolved in the filtrate is a relatively pure unoxidized resin or rosin acid soap. Both can be used in the industry directly without any further purification.

The ketone used for separating the two soap types may be any ketone containing not more than six carbon atoms to the molecule such as an aliphatic ketone and containing dissolved water in the proportion of 5 to 10 percent of the ketone. Particularly satisfactory results are obtained when the proportion of water is between 5-8 percent of the ketone. The percent expressed is percent by weight. If the percentage of water is lower than the minimum range, the fatty acid soap separation will not be as free as the resin soap. On the other hand the higher percentage of water in the ketone will introduce more fatty acid soap in the separated resin soap. To obtain the optimum separation, the percentage of water in the ketone should be between 7 and 8 percent.

Typical ketones that illustrate the class that may be used are acetone, methyl ethyl ketone, diethyl ketone, and methyl propyl ketone. In case the ketone selected does not have such solvent power for water to dissolve the required

percentage, then the solvent power of the said ketone may be increased by incorporating sufficient acetone with it. Thus the selected ketone, if not itself acetone, may contain 10 to 40 percent acetone, the higher the ketone the larger the proportion of acetone required within the range stated.

Example 1

One hundred parts of the floating soap containing about 35 percent water, are thoroughly mixed with 250 parts of anhydrous acetone at room temperature and the resulting mixture filtered in order to remove substantially most of the water and dry the crude soap out of contact with air. The resultant dry soap on the filter is then washed with several portions of acetone containing 8 percent of water and totaling about 500 parts. After the washing is completed, the filter cake is then removed, dried to remove the adhering acetone at low temperature and weighed. This was 38 parts, and had a molecular weight of 305 (304 being the theoretical for pure sodium oleate) showing the relatively high purity of the soap.

To the filtrate which contained all of the sodium salts of resin or rosin acids, acetone and water, was added an excess of toluol or benzol and the mixture evaporated to dryness by distillation. By this method both acetone and water are removed by partial pressure, i. e., low temperature, distillation and the soap after removing the hydrocarbon solvent is found to be substantially anhydrous. The anhydrous material was resin soap suitable for sizing purposes and weighed 30 parts. Its average molecular weight corresponded closely to that of the sodium salts of the mixed acids of commercial rosin.

Example 2

One hundred parts of floating soap containing about 30 percent water was mixed with 500 parts of anhydrous acetone and agitated thoroughly so that the water in the soap is well dissolved in acetone. This makes the water content of acetone about 6 percent. The mixture is filtered and washed with 94 percent acetone and the filter cake dried and weighed. The weight was 40.4 parts. Its average molecular weight was 307 and the presence of a small amount of high molecular weight sodium resinate was detected. The acetone filtrate was evaporated by partial pressure distillation at a temperature between about 80 to 110° F., usually and preferably below 100° F. in vacuum or inert atmosphere. The resulting dry sodium resinate or abietate which was 32 parts, had the average molecular weight of sodium salts of mixed commercial rosin acids. The sodium resinate contained traces of fatty acid soap but was just as good a sizing material as in Example 1. The sodium soap, however, appeared to have better detergent properties than the product of Example 1.

Example 3

One hundred parts of floating soap reported to contain about 35 percent water was first dried by washing with 550 parts of anhydrous acetone divided into several portions. The wet cake of 100 gms. was dried in a vacuum desiccator until it had a constant weight. This was 71 gms. showing that the reported water content given by the manufacturer was a little too high. This soap was of cream or brownish yellow color in contrast with air dried soap which is dark brown in color and has a fishy odour.

The odour of this soap was definitely non-fishy, although not very pleasant. It appeared to be some sort of sulphide odour. The vacuum desiccator dried sample which weighed 70 grams was further washed with several portions of acetone, totaling about 500 cc., the filtered cake was dried in a vacuum desiccator to remove acetone, and weighed. The weight was 37.5 grams and had good detergent properties. Its average molecular weight was 305 as in Example 1, and was a relatively pure fatty acid soap. The filtrate when freed from acetone and water and dried out of contact with air was found to be 30.5 grams and had an average molecular weight of 358 as soap, or 336 as rosin acid. It was quite satisfactory as a sizing material.

Example 4

One hundred parts of wet kraft soap containing 35 percent water as reported by the manufacturer, but actually 30 percent as shown in Example 3 and the same source material, was spread out on a watch glass and dried in an oven in a current of nitrogen gas at 105° C. until it lost no further weight. The dry weight so obtained was 70.3 parts and checked with that in Example 3, within experimental errors. This was then triturated with 93 percent acetone as in Example 3, and washed and filtered and dried. The filter cake on dry basis weighed 38.6 grams and the filtrate after freeing from acetone and water weighed 30.6 grams. In quality both soaps were substantially as good as in Example 3.

In a modification of the invention, the higher fatty acids in the floating soap are displaced by abietic acid before the sodium abietate is separated.

In this modification, there is first made a mixture including the floating soap in substantially dry condition, added abietic acid or rosin in amount approximately equivalent to the higher fatty acids present in the floating soap, and an anhydrous volatile ketone. The mixture is then warmed suitably by boiling the mixture under a reflux condenser, until the mixture which originally contained much undissolved material becomes a practically clear solution. The solution is then cooled approximately to room temperature or lower, whereupon sodium abietate is deposited in solid form. There is left in solution free fatty acids corresponding to the major part of the fatty acids originally combined with sodium in the floating soap.

As the ketone to be used in this modified method, there is used one containing about 6 carbon atoms to the molecule, say 4 to 8 carbon atoms, suitable materials being methyl butyl ketone, methyl isopropyl ketone, dipropyl ketone and ethyl propyl ketone. The ketone used should be substantially anhydrous and should be a good solvent for higher fatty acids in the free condition but a poor solvent or substantially a non-solvent for sodium abietate at room temperatures.

An example of this displacement method of separating the fatty acids of floating soap is the following:

Floating soap is dewatered as by thorough washing with substantially anhydrous acetone, or, the soap is dewatered by forming a mixture of the wet floating soap with toluene, xylene, or like hydrocarbon liquid, distilling the mixture so that the said liquid on distillation removes water, condensing the distilled vapors, separating the condensate into two layers, returning the hydro-

carbon liquid to the still, continuing the operation until there is left a practically anhydrous mass of the floating soap suspended in an excess of the hydrocarbon liquid in the still, separating the thus dried soap from the liquid by filtration, and removing adhering liquid from the separated soap by evaporation, preferably at a temperature below the temperature of melting or softening of the soap.

Of the dewater floating soap, 100 parts are mixed with abietic acid in amount equivalent to the fatty acid present in the soap (53.5 parts of abietic acid), this proportion of abietic acid for most other floating soaps being about 30 to 60 parts, the exact amount required being calculable from the analysis of the floating soap used. Eighty parts of anhydrous methyl butyl ketone are then added and the whole is refluxed for one-half hour. (In general 80 to 90 parts will suffice.) Originally the mixture contains much undissolved material but a chemical change occurs as the refluxing is continued that makes the solids present dissolve substantially completely. This change is the replacement of higher fatty acids of the floating soap by abietic acid, to give additional sodium abietate. After the solution is effected, it is cooled to approximately room temperature or lower if desired, during which cooling sodium abietate separates in solid form. There is thus obtained a satisfactory yield of sodium abietate. The higher fatty acids in free condition are left in solution.

The mixture is then subjected to processing to separate the solid sodium abietate from the solution of the higher fatty acids; as by centrifugal separation or by filtration. In any case, the separated sodium abietate is washed, say in the centrifuge basket or on the filter, with fresh methyl butyl ketone. The residue after washing is then warmed to evaporate the adhering ketone, as, for example, to about 60° to 80° C. The sodium abietate so recovered is suitable for use in paper sizing.

The fatty acids that remain in solution are recovered by evaporation of the volatile ketone and used in the manufacture of soap or for other purposes requiring fatty acids as raw material.

It will be understood that certain details given are for the purpose of illustration, not restriction of the invention, and that variations within the spirit of the invention are intended to be included within the scope of the appended claims.

I claim:

1. In a method of separating a crude wet soap mixture of high molecular weight of the hydro aromatic resin acid and unsaturated fatty acid as occurring in the kraft pulp industry the steps of drying the crude wet soap mixture under non-oxidizing conditions by washing the crude wet soap with an aliphatic ketone having not more than eight carbon atoms, adding thereto abietic acid in amount substantially equivalent to the said fatty acids present, warming the mixture whereby a solution results and the abietic acid replaces fatty acids from the said salts, cooling the mixture, and separating the resulting precipitate of sodium abietate from the remaining solution of fatty acids in the ketone.

2. In a method of separating a crude wet soap mixture of high molecular weight of the hydro aromatic and unsaturated fatty acid type occurring as the crude wet floating soap mixture of the kraft pulp industry the step of first drying the crude soap by washing the same under non-oxidizing conditions with a substantially anhy-

drous aliphatic ketone of not more than about 8 carbon atoms having a substantial water absorption capacity and low solubility for the soap and then separating the dry soaps from each other by adding to the dry soap mixture a hydrous ketone selected from the group consisting of acetone, methyl ethyl ketone, di-ethyl ketone, methyl propyl ketone and mixtures of acetone and one of said higher ketones, blended with 5 to 10% of water in which the resin soap is preferentially soluble and then separating the dissolved soap solution from the insoluble soap residue.

3. In a method of separating a crude wet soap mixture of high molecular weight of the hydro-aromatic and unsaturated fatty acid type occurring as the crude wet floating soap of the kraft pulp industry, the steps of first drying the soap by adding to the soap a volatile aromatic hydrocarbon and azeotropically distilling to re-

move the water and added hydrocarbon, adding to the dry soap mixture an aliphatic ketone having not more than 8 carbon atoms and abietic acid in amount substantially equivalent to the said fatty acids present, warming the mixture whereby a solution results and the abietic acid replaces fatty acids from the said salts, cooling the mixture, and separating the resulting precipitate of sodium abietate from the remaining solution of fatty acids in the ketone.
